COMBINED ELECTRONIC KEYBOARD AND STAND THEREFOR

George F. Minka, Torrance, Calif., assignor to The Data
Systems, Inc., Torrance, Calif.

Filed Oct. 19, 1970, Ser. No. 25,557

Term of patent 14 years

Int. Cl. D14—02

U.S. Cl. D26—5

Fig. 1.

Fig. 6.

Fig. 7.

Fig. 2.

Fig. 3.

Fig. 4.

Fig. 5.

FIG. 1 is a perspective view of a combined electronic keyboard and stand therefor showing my new design;

FIG. 2 is a front elevation;

FIG. 3 is a rear elevation of the keyboard thereof, a portion of the stand being omitted for convenience of illustration;

FIG. 4 is a top view;

FIG. 5 is a bottom view;

FIG. 6 is a right side elevation; and

FIG. 7 is a left side elevation of the keyboard thereof, a portion of the stand being omitted for convenience of illustration.

I claim:

The ornamental design for a combined electronic keyboard and stand therefor, substantially as shown.
